D. WILKINSON.
CANAL LOCK GATE.

Patented Aug. 17, 1835.

Aug. 17, 1835

David Wilkinson of Albany, New York
Letters Patent

The Schedule referred to in these Letters Patent and making part of the same containing a description in the words of the said David Wilkinson himself of his improvement in Gates for Canals.

Be it Known that I David Wilkinson of Cohoes, Albany County, State of New York, have made an improvement in Gates for Canal Locks, which is described as follows.

This Gate is constructed in the usual manner. The improvement consists in the mode of adjusting the friction Roller to the quadrant or circular rail way the rider to guide the chain on the capstan - a catch or pull in the head of the capstan to prevent its being turned in a wrong direction, and the self-adjusting valve gate. The friction roller is adjusted by means of a slide bar passing through the wooden bars of the Gate bearing on a sliding frame or box which contains the friction Roller. This rod is raised or lowered by a nail and screw on the top of the rod. The mode of suspension may be various, to suit circumstances. The rider placed at the bottom of the capstan - to guide the chain on the capstan is constructed by having a thimble to pass around the track, the under edge of which is made in a spiral form with a tube attached to the same through which the chain passes. The top of the capstan into which the lever is inserted is made so as to contain a click or pull against which the lever may catch this will prevent its ever being turned the wrong way. The self-adjusting valve gate is constructed so as to open by the pressure of the water to effect this the gate is hung by a hinge bar or joint. There are two connecting rods, fixed on the back side of the main gate at right angles to the lower edge of the valve and extending to the top of the gate which are held down by a screw at the top, or they may be held down in any other manner. These bars. Gate may be placed vertically as may be deemed convenient in some cases. Or the valve gate may drop by the force of the water and close upward by

the force of the screw or lever. Operation. When the gate is shut it moves along the quadrant or circular rail way by the use of the chain and capstan. The lock being full of water, the catch on the screw which holds down the valve gate is detached and the screw being so graduated as to travel by the force of the water, the pressure of water opens the valve which gives motion to the screw. When the screw is sufficiently high another pull falls into gear and holds it up. When the water is equalized in the upper and lower locks, the screw by its own weight closes the valve, and the pull holds it fast till detached by hand or the fall is opened with and the screw being so graduated as to remain stationary without the assistance of the pull or catch.

The invention here claimed and desired to be secured by Letters Patent consists in the before described mode of adjusting the friction roller in the quadrant or circular way the rider to guide the chain on the capstan - the open head with pulley of the capstan and the self-adjusting valve gate.
